SCRAP EJECTOR AND STACKER

Lyle Blanford, Chicago, Ill., assignor to Continental Can Company, Inc., New York, N. Y., a corporation of New York

Application November 17, 1934, Serial No. 753,536

9 Claims. (Cl. 271—72)

The invention relates to a device for handling and disposing of scrap which has been ejected from an automatic strip press.

Heretofore scrap has been discharged promiscuously from automatic strip presses and the floor near the presses becomes littered with scattered pieces of scrap. Serious injuries have occurred to the operators of the presses from cutting of their feet and ankles on the ragged, sharp edges of the scrap lying around their machines, and there is much time lost and labor required in disposing of the scattered piles of scrap. It is to avoid these accidents and to save time and labor that the present scrap ejector and stacker 15 has been devised.

An object of the invention therefore is to provide a mechanical device which will take the sheets of scrap from which blanks have been punched as they leave the press and arrange them 20 in compact piles which may be removed at intervals as a unit.

A further object of the invention is to provide a device of the above type which is driven in timed relation to the press and which will accomplish the above results automatically and without 25 the attention of the operator of the press.

These and other objects will in part be obvious and will in part be hereinafter more fully disclosed.

30 Referring to the drawings:

Figure 1 is a plan view of a piece of scrap from which blanks have been punched.

Figure 2 is a top and front view of one side of a press with an automatic scrap ejector and stacker driven thereby, looking in the direction of the arrow *d* in Figure 3.

Figure 3 is a view in side elevation of the press and stacking device.

Figure 4 is a view partially in plan and partially 40 in section taken on the line 4—4 of Figure 3.

Figure 5 is a view in front elevation of the stacking device and showing in broken lines the stack being removed.

Figure 6 is a sectional view taken centrally 45 through the hinged stacking plate.

Figure 7 is a sectional view showing the manner in which one of the rods which receives the scrap is mounted upon its base.

Figure 8 is a perspective view of the base plate 50 for the stacking rods.

Figure 9 is a side view of the ejecting drum and stacking plate.

Figure 10 is a sectional view taken on the line 55 10—10 of Figure 9.

55 The invention relates to a device for automati-

cally handling and disposing of scrap which has been ejected from a strip press. The illustrated device for carrying out the invention consists of a rotating drum which is mounted on a suitable pedestal at one side of the strip press. The drum 5 is driven by a suitable chain and sprockets from the crank shaft of the press and is mounted with its face tangent to a plane containing the surface of the bed of the strip press. An ejector finger or dog protrudes through an opening in the face of the drum and is so located as to catch in the opening in the scrap left by the first blank to be punched and in each strip just after the last blank is punched. As the drum rotates, the scrap held by the ejector finger is pulled out of 10 the press and carried around on the rim of the drum. A flat spring is provided which presses against the drum and holds the scrap firmly against the rim thereof. As the drum carries the ejector finger to a position approximately 270 degrees from the point where it first engaged the 15 scrap, a cam roller mounted on the ejector finger rides upon a suitable release cam and the ejector finger is depressed below the surface of the drum thereby releasing the scrap which has at 20 this time been carried clear of the spring. When released, the scrap drops onto a stacker plate which is pivoted about a suitable hinge and timed to rise and receive the scrap as it is released. The scrap resting on the stacker plate which has 25 risen to pick up the same is now carried by the stacker plate to a point where it falls therefrom and drops upon two upright rods. These rods are mounted on a suitable support or platform directly under the stacker plate and are spaced 30 from one another to correspond with the blank openings in the scrap. In this manner, after repeated operations of the ejector drum and stacker plate, the scrap becomes arranged in a 35 neat pile over the upright rods on the platform 40 and can be carried away from the machine as a unit at desired intervals. The ejector drum and stacker plate are driven in timed relation to the press and the placing of the scrap over the upright rods is entirely automatic and requires no 45 attention from the operator of the press.

Referring more in detail to the drawings and more particularly to Figures 2 and 3 thereof, an automatic press of well known type is diagrammatically shown and indicated at *P*. The press 50 as shown is of the usual construction having a die and platen for automatically punching blanks from sheets of metal. After the blanks have been punched out of the sheet of metal in the well known step by step manner, the sheet be- 55

comes scrap. It is for the purpose of handling this scrap that the new automatic scrap ejector and stacker plate has been devised.

Figure 1 of the drawings shows a piece of scrap 5 S from which blanks have been punched and the openings formed by the die punches are indicated at s, s. The ejecting and stacking device comprises three units: an ejecting drum 1, a stacking plate 2 and a loading platform or support 3 upon 10 which the scrap is piled in succession by the automatic functioning of the ejecting and stacking units 1 and 2. After the loading platform 3 becomes full, it may be removed by a hand truck to another part of the factory, carrying the scrap 15 as a unit, and an empty platform substituted without interruption of the press or attention of the operator.

The ejector unit 1 comprises a drum 3' which is rotatably supported by a suitable bracket 4 20 which is in turn mounted on a stationary pedestal 5 at one side of the press. The axis of the drum is at an angle to the pedestal so as to place the face of the drum tangent to the plane of the bed of the press. The drum is mounted in this manner so that the scrap as it passes to the rim 6 of the drum will not be twisted. The pedestal which supports the drum is placed to one side of the press, the distance therefrom being sufficient so that when the last blank is being punched from 30 the scrap, the opening left by the first blank will be advanced to a point directly over the drum with the scrap sheet substantially tangent to the rim of the drum. This aids in the easy wrapping of the scrap sheet about the drum. The stacking device 2 is also supported by the pedestal 5, a detail description of which will be given later.

The drum is driven from the crank shaft of the press and revolves twice for every strip handled by the press. The driving means for the drum 40 comprises suitable sprockets 7 and 8 and a sprocket chain 9 linked therebetween. An idler sprocket 10 is adjustably mounted on the supporting bracket 4 for taking up the slack in the sprocket chain 9. The sprocket 8 is keyed to a driven shaft 11 of the press and the sprocket 7 is attached to and turns with a hub 12 of a miter gear 13. The miter gear 13 in turn drives a miter gear 14 which is keyed to a central driving shaft 15 on which the drum is mounted. A suitable housing for supporting the driving shaft 15 is afforded by bushings 16 (only one shown) mounted in the stationary drum supporting bracket 4.

The ejecting drum itself is cast in a form similar to a flat rimmed pulley having a central hub 17 and supporting spider arms 19 extending from the hub and integrally attached to the rim 6 of the drum. The hub 17 of the drum is keyed to the driving shaft 15 and held from endwise movement by a suitable bolt and washer. One of said spider arms has a boss 19' which is cast integrally therewith near the inner side of the rim of the drum. For counterbalancing the drum, a similar boss 20 is cast on the opposed spider arm to the one carrying the boss 19. The boss 19 is bored out and carries bushings 21 which support an oscillatably movable shaft 22. Secured to one end of the shaft 22 is an ejector finger or dog 23, one end of said dog being notched and brought to a point 24 which normally extends through an opening in the rim of the drum, whereby it operates to catch in the opening left by the first blank punched from the scrap when the sheet is projected over the drum by the feed of the press. 70 The position of the dog as it catches the scrap is

best shown in dotted lines in Figure 9 of the drawings.

As will be noted in Figure 5 of the drawings, the drum assembly 1 is provided with a cover plate 1a secured by screws 1b threaded in suitable bosses 1c, shown in Fig. 10. The purpose of this cover plate is obvious and merely keeps dust and dirt from the working parts within the drum.

Secured to the other end of the shaft 22 is a cam roller arm 25 which carries a cam roll 26. The dog 23, shaft 22 and cam roller arm 25 operate as a unit and are held in position with the end 24 of the dog projecting through the rim of the drum by a spring 26'. The dog is adjustable as to the distance it projects through the opening in the drum by means of a set screw 27 carried by the cam arm 25.

Means for releasing the scrap from its engagement with the dog 23 is provided by the action of a dog release cam 28 which is mounted on a support 29, the latter being clamped to the hub of the bracket 4. The release cam 28 contacts with the cam roll 26, retracting the end 24 of the dog and thus releases the scrap. The release cam support is adjustable by means of a set screw 29a about the hub 4 to time the releasing of the dog to different lengths of scrap. A flat spring 30 is carried by a suitable bracket 31 which is attached to the side of the press by means of a bracket 31a. The spring 30 adapted to hold the scrap firmly against the rim of the drum until the dog is released from its grip upon the scrap by action of the release cam and cam roller.

The stacking unit 2 is supported by a suitable bracket 32 which is attached to the drum supporting bracket 4 beneath the drum by suitable screws 33. The bracket 32 extends outwardly beyond the rim of the drum and has attached to the outer end thereof, by means of the rivets 35, a stacker plate supporting bracket 34 (see Figure 6 of the drawings). Hinged to the bracket 34 by means of a hinge pin 36 is a stacker plate 37. The stacker plate is cut out as indicated at 37'' so that it will conform to the face of the drum and may be mounted in close proximity thereto. The stacker plate rises and falls in an arc in timing with the rotation of the drum as the scrap is released from the drum, for the purpose of receiving the scrap and placing the same on the loading platform 3. The drive for the stacker plate consists of an eccentric 38 mounted on the face of a suitable disk 39 which is rotated by the shaft carrying the miter gear 13. The stacker plate 37 has a rock arm 40 which is connected to the eccentric 38 by means of a link 41 and is thus rocked thereby.

The loading platform 3 is supported by suitable angle irons 42 which raise it from the floor sufficiently to clear the hand truck for carrying off the same. Two upright rods 43 are adjustably mounted on the platform 3 and held by supports 44 having suitable bolts 45 extending through the supports and through slots 46 in the platform. The rods 43 are set and spaced one from another so as to enter the end holes in the scrap as it is delivered by the stacker plate 37. As may be seen in Figure 7 of the drawings, the rods are mounted at a slight angle from the vertical by means of a wedge block 47 located between the supports 44 for the rods and the platform. This is desirable because the scrap, as it straightens out after being held against the ejector drum, strikes the side of the press and is forced away from it as it falls over the stacker rods. The angle at which the latter are mounted is arranged to carry the scrap 75

away from the side of the press and permit it to lay flat.

From the above description the operation of the machine should be apparent. The ejector drum driven by a chain from the crank shaft of the press revolves twice for every strip handled by the press. The ejector dog is so located that it catches in the opening of the scrap left by the first blank to be punched in the strip, just after the last blanks are punched. As the ejector drum revolves, the scrap held by the ejector dog is pulled out of the press and carried around on the rim of the ejector drum. The flat spring 30, pressing against the ejector drum, holds the scrap firmly against the face thereof. As the drum carries the dog to a position approximately 270 degrees from the point where it first engaged the scrap, the cam roller controlling the ejector dog strikes and rides upon the release cam, depressing the ejector finger below the surface of the drum and thus releases the scrap which has by this time been carried clear of the spring 30. When the sheet of scrap is released, it drops onto the stacker plate, contacting with the same at the angle thereof and gravity will tend to turn the sheet in a counterclockwise direction as viewed in Figure 3, said sheet turning about the edge resting on the stacker plate as a center. This stacker plate is so positioned relative to the rods that the rods will pass through the openings in the sheet. The member 37' of the stacker plate is rising during this time, and will aid in positively bringing about this turning down or inverting of the scrap sheet over the rods 43. The stacker plate now returns to its former position and the ejector drum makes a complete idle revolution while the press is punching out the first part of the next strip. As the punching is completed, the ejector drum will have again reached the position where it is ready to take hold of the next strip. By successive cycles of operation of the ejector drum and stacker plate, the loading platform soon becomes piled with scrap which may be moved as a unit from the press and an empty platform substituted therefor.

While the invention is useful in any type of strip press and the part cut out referred to as a blank, it is particularly adapted for a die press which cuts and forms can ends from a strip of metal.

It is obvious that minor changes in the details of construction and the arrangement of the parts may be made without departing from the spirit of the invention as set forth in the appended claims.

Having thus described the invention, what I claim as new and desire to secure by Letters Patent, is:

1. A device for ejecting and stacking sheets of scrap from which blanks have been punched, comprising a stackholder having upright rods disposed so as to enter openings in the scrap, and a piling mechanism associated therewith including a rotating drum, a device carried by the drum for positively engaging the sheets of scrap in succession as they are discharged from the press, means for releasing said engaging device, and means for delivering each sheet to the stackholder in succession when openings therein are in proper alignment with the upright rods carried by the stackholder.

2. A device for ejecting and stacking sheets of scrap from which blanks have been punched, comprising a stackholder having upright rods disposed so as to enter openings in the scrap, and a

piling mechanism associated therewith including a rotating drum, a dog carried by the drum for engaging the sheets of scrap as they are discharged from the press, means for releasing said dog, and means operating independently of the drum and in timed relation therewith for receiving the sheets one after another and placing them in successive order over the upright rods carried by the stackholder.

3. A device for ejecting and stacking sheets of scrap from which blanks have been punched, comprising a stackholder having upright rods disposed so as to enter openings in the scrap, and a piling mechanism associated therewith including a rotating drum, a dog carried by the drum for engaging the sheets of scrap as they are discharged from the press, means for holding the sheet of scrap in contact with the face of the drum as it rotates, means for releasing said dog, and means operating independently of the drum and in timed relation therewith for receiving the sheets one after another and placing them in successive order over the upright rods carried by the stackholder.

4. A device for ejecting and stacking sheets of scrap from which blanks have been punched, comprising a stackholder having upright rods disposed so as to enter openings in the scrap, and a piling mechanism associated therewith including a rotating drum, a device carried by the drum for positively engaging the sheets of scrap in succession as they are discharged from the press, means for releasing said engaging device, a member associated with said drum onto which said sheet of scrap falls and about which said sheet turns so as to place the sheet over the upright rods carried by the stackholder, a plate carried by said member, and means for moving said member to cause said plate to force the scrap into position so that it will drop over the rods carried by the stackholder.

5. A device for ejecting and stacking sheets of scrap from which blanks have been punched, comprising a stackholder having upright rods disposed so as to enter openings in the scrap, and a piling mechanism associated therewith including a rotating drum, a device carried by the drum for positively engaging the sheets of scrap in succession as they are discharged from the press, means for releasing said engaging device, a member associated with said drum onto which said sheet of scrap falls and about which said sheet turns so as to place the sheet over the upright rods carried by the stackholder, a laterally extending plate carried by said member, means for pivotally supporting said member, and means for oscillating said member in timing with the rotation of the drum whereby said plate is caused to positively force the sheet of scrap to turn on said supporting member for the stacking of the scrap on the rods of the stackholder.

6. A device for ejecting and stacking sheets of scrap from which blanks have been punched, comprising a stackholder having upright rods disposed so as to enter openings in the scrap, and a piling mechanism associated therewith including a rotating drum, a dog carried by the drum for engaging the sheets of scrap as they are discharged from the press, means for holding the sheet of scrap in contact with the face of the drum as it rotates, means for releasing said dog, and a member associated with said drum onto which said sheet of scrap falls and about which said sheet turns so as to place the sheet over the upright rods carried by the stackholder.

7. A device for ejecting and stacking sheets of scrap from which blanks have been punched, comprising a stackholder having upright rods disposed so as to enter openings in the scrap, and a piling mechanism associated therewith including a rotating drum, a dog carried by the drum for engaging the sheets of scrap as they are discharged from the press, means for holding the sheet of scrap in contact with the face of the drum as it rotates, means for releasing said dog, a member associated with said drum onto which said sheet of scrap falls and about which said sheet turns so as to place the sheet over the upright rods carried by the stackholder, a plate carried by said member, and means for moving said member to cause said plate to force the scrap into position so that it will drop over the rods carried by the stackholder.

8. A device for ejecting and stacking sheets of scrap from which blanks have been punched, comprising a stackholder having upright rods disposed so as to enter openings in the scrap, and a piling mechanism associated therewith including a traveling member, a device carried by the

traveling member for positively engaging the sheets of scrap in succession as they are discharged from the press, and means operating independently of the traveling member and in timed relation therewith for receiving the sheets 5 one after another and placing them in successive order over the upright rods carried by the stackholder.

9. A device for ejecting and stacking sheets of scrap from which blanks have been punched, 10 comprising a stackholder having upright rods disposed so as to enter openings in the scrap, and a piling mechanism associated therewith including a rotating drum, a device carried by the drum for positively engaging the sheets of scrap in 15 succession as they are discharged from the press, means for releasing said engaging device, and a hinged member associated with said drum onto which each sheet of scrap falls as it is released from the drum, said hinged member being rocked 20 in timed relation with the delivery of the scrap from the drum so as to place each sheet over the upright rods carried by the stackholder.

LYLE BLANFORD.
